KITE

Jack A. Chapman, 1014 N. Bagley, Dallas 11, Tex.

Filed Jan. 17, 1958, Ser. No. 709,489

9 Claims. (Cl. 244—153)

This invention relates generally to kites. More particularly the invention has reference to a kite of generally circular configuration, having a particularly improved, dished formation adapted to increase measurably the adaptability of the kite for sustained flight in relatively light winds.

The main object of the invention is to provide a kite of generally improved construction, so designed that it can be flown in a wind which is insufficient to support an ordinary kite.

Among more specific objects of the invention are the following:

To provide a kite the full area of which will be exposed broadside or perpendicularly to the wind currents;

To so design the structure that pressurized air will be forced about the contoured section of the kite, providing extra lift;

To provide "a wrap-around" contour to the kite, which will give the same a significant lift in all positions of flight;

To impart measurably increased stability to the kite, through a flanged peripheral construction;

To provide an airfoil characteristic in the kite, which will be applicable to not only the circular shape illustrated and described by way of example, but also, to various other configurations such as octagonal, square, and triangular kites;

To facilitate assembly or disassembly of the kites;

To provide a kite which, despite its relatively low cost, will still be rugged and capable of withstanding heavy use, so that it can be adapted not only for pure amusement purposes, but also for use in the military services, by meteorological authorities, etc.; and

To provide a kite which can be die formed from thin sheet aluminum or other light weight materials.

Other objects will appear from the following description, the claims appended thereto, and from the annexed drawing, in which like reference characters designate like parts throughout the several views, and wherein:

Figure 1 is a rear elevational view of the kite, viewing the back thereof;

Figure 2 is a sectional view diametrically through the kite, substantially on line 2—2 of Figure 1;

Figure 3 is a side elevational view of the kite in flight;

Figure 4 is a reduced elevational view of the kite, showing the side thereof exposed directly to the wind currents, that is, showing the kite as seen from the ground; and

Figure 5 is a still further reduced, diagrammatic view showing the flight pattern of the kite.

Referring to the drawing in detail, generally designated at 10 is the body of the kite constituting the present invention. In the illustrated example, the kite is of circular configuration. However, it could be otherwise shaped, as indicated in the foregoing objects.

In any event, it may appropriately be considered that although the skin of the kite is continuous over the full area against which the air currents impinge, in actuality it may be appropriately stated that the area of the skin

2

is divided into two segments, in the sense of the airfoil characteristics thereof. These are a larger or lower segment 12 (see Figure 4) and an upper or smaller segment 14. Segment 12 is bounded by radial lines A, C radiating from the center point of the kite, and by a portion D of the kite periphery. Said portion D extends the full distance between the outer ends of the radial, imaginary lines A, C, over an angular distance of 225 degrees of the full circumference of the kite.

10 The segment 14 is smaller and is bounded by radial lines A, C and by a line B constituting the remainder of the periphery of the kite. The line B extends, as will be understood, through the remaining portion of the kite circumference, that is, through 135 degrees.

15 The particular characteristics of the segments 12, 14 in relation to one another, for the purpose of producing improved flight characteristics when impinged upon by air current, will be described in greater detail hereinafter, during the discussion of the operation of the kite.

20 Considering the construction of the kite, the body 10 includes a frame generally designated at 16, over which is stretched the skin 18 of the kite, the frame 16 and skin 18 cooperating to define said body. The frame is so constructed that through the full angular distance 25 measured along the arcuate periphery of segment 12, there is a rearwardly directed flange 19 which is a 225 degree segment of a frustum of a cone. The ends of the flange have been designated at 20 in Figure 4, and are in line with the radial, imaginary dividing lines A, C that divide the segments 12, 14 from one another.

25 Over the remaining portion of the periphery of the kite, that is, over the angular distance measured along the arcuate segment 14, there is a flange portion 22 which, viewed in cross section at any point along its 30 length (see Figure 2) is arcuately outwardly bowed, providing a forwardly rounded leading edge on the airfoil. The flanges 19, 22 are formed at their back edges with inwardly directed lips 24, 28 respectively. Lip 24, and for that matter the entire back edge of flange 19, is 35 curved on a radius slightly greater than lip 28. As a result, the end portions 26 of the lip 24 are angled inwardly or offset, to connect the lips 24, 28 (see Figure 1) in a manner effective to provide a continuous lip over the full circumference of the kite.

40 Bisecting the lower segment 12 is a stabilizing fin 30, which radiates from the center point of the kite, projecting radially outwardly beyond the periphery of the skin. Bracing the fin and providing a connection between the fin and the frame of the kite are braces 32, 33 (see Figure

50 2). The fin would of course be suitably covered, and not only serves to provide a slight weight at the bottom of the kite intended to maintain the kite in an upright position with its segment 14 located as the upper segment, but also, serves to stabilize the kite to prevent rocking of the same about its center. The fin, thus, discharges the 55 function of a tail on a conventional kite. In this connection, it may be that in some commercial embodiments, the fin might be omitted and a cloth tail might be used to provide the weighting and stabilizing action.

60 The lower segment 12, as previously noted, has an arcuate flange portion 19 extending the full angular distance along the arcuate outer edge of said lower segment 12. Flange portion 19 is segmentally frusto-conical. The area of the segment 12 inwardly of the flange

65 portion 19 has been designated at 37 in Figure 4, and constitutes the area bounded by radial lines A and C and by the inner edge 31 of flange portion 19. This area is segmentally, shallowly, conical and the several struts 34 extend radially thereof and lie as parts of the shallow cone segment, so that when the skin is stretched thereover, the segmentally shallowly, conical body part 70 37 of lower segment 12 is produced. Struts 34, at their

outer ends, are merged into struts 35 of flange portion 19, and braces 36 are secured to and extend diagonally between struts 34 and 35.

Frame 16 also includes radial struts 38, over which is stretched that part of the skin that falls in the area of the upper segment 14. The radial struts 38 also lie in a segment of a shallow cone, the shallowly conical body of the segment 14 being designated at 39 in Figure 4 and merging smoothly and gradually into the arcuately, outwardly bowed flange portion 22 of the segments 12, 14 respectively. In fact, the body parts 37, 39 of the segments 14 in actuality constitute different segments of the same shallow cone, although the conically segmental body part 37 has a greater radius than the conically segmental body part 39, since it continues fully to the inner edge 31 of flange portion 19, whereas the body part 39 merges, at a shorter distance from the center point of the kite, into the rounded flange portion 22.

The radial struts 38, at their outer ends, are fixedly secured to arcuate extension struts 40 which are curved in such a manner that when the skin is stretched thereover, the curved flange portion 22 is produced. No bracing is here needed, in view of the bracing action produced by the smooth merger of the straight struts 38 into the arcuate extension struts 40.

A bridle includes an upper line 42, a lower line 44, and side lines 46, radiating from a common connection 47 to points 48, 50, and 52 of the frame, at which points the lines of the bridle are connected to the frame by means of eyes or equivalent fasteners. At the common connection 47 of the lines of the bridle, said lines are connected to a tethering or anchoring line 54. Point 48 will be noted as disposed a short distance above the center point 56 of the frame, in vertical alignment therewith, while point 50 is disposed upon the stabilizing fin strut 30 intermediate the ends of this strut, in diametrically aligned position in relation to the point 48. Points 52 are disposed upon the periphery of the frame, symmetrically in respect to and at opposite sides of the points 48, 50 as clearly seen in Figure 4.

In use of the kite, the particular manner in which the air currents impinge thereupon produce the highly desirable flight characteristics. As will be seen from Figure 3, air currents traveling substantially horizontally, that is, generally parallel to the ground surface, are designated by arrows E. These impinge upon the surfaces of the upper and lower segments. The air impinging upon the upper segment 14 travels upwardly, as shown by arrows F in Figure 3. These air currents continue about the arcuate surface of flange portion 22, as shown by arrows G in Figure 3. The air currents so impinging impart lift to the kite in the direction of an arrow H in Figure 3.

Other air currents E impinge upon the area of the lower segment 12. These flow radially outwardly along lines designated by arrows J, imparting a "push" or lifting action along the line K shown in Figure 3, this lifting action being along a line extending rearwardly upwardly from the kite while the lifting action shown at H is along a line extending forwardly upwardly from the kite.

The particular construction is one which has a highly desirable characteristic of an airfoil, the application of this feature, analogous to that found in an airplane wing, being such as to make it possible to fly a kite in a wind which is insufficient to support an ordinary kite. Further, the aerodynamic characteristics of the kite are such as to permit the full area of the kite to be exposed perpendicularly, or substantially so, to the wind currents, when the kite is near ground level, with pressurized air being forced about the marginal portions of the kite to add extra lift. The particular construction of the marginal portions, further, gives the kite significant lift in all positions of flight.

As seen from Figure 5, the fact that the kite is perpendicular to the wind on take-off is very important, as the lift is at the maximum in this position. The kite does

not fly in this position, but the rounded leading edge lets the point of lift move along the leading edge as the kite changes its angularity to the ground.

It will be understood that in making reference to the fact that the kite does not fly in the take-off position, this term is intended to mean that the kite is not perpendicular to the direction of the wind when in its normal flying position shown as the uppermost position in Figure 5. Of course, with the lifting force applied to the kite in the mentioned perpendicular position, which is substantially that shown as the lowermost position in Figure 5, the kite will fly at least momentarily, in the sense that it will move upwardly from said lowermost position. In other words, from the lowermost position, with the strong lifting force directed thereagainst, the kite rises through the several positions shown in Figure 5 to its normal "flying" position, which as previously noted is the uppermost, Figure 5 position.

Before concluding the discussion of the construction, it is appropriate to note that the body parts 37, 39 of segments 12, 14 respectively, together define a main part generally designated 60, of the shell-like body 10 of the kite. Said main part 60 may be considered as comprising the entire portion of the body that is of the previously discussed shallowly conical shape, that is, the generally circular, shallowly-dished central portion, to different segments of the periphery of which the flange portions 19, 22 are secured.

It is also appropriate to note, to provide a full understanding of the construction, particularly with reference to the claims appended hereto, that the front of the kite can be considered as the part that is faced toward the air currents impinging against the kite, while the rear portion can be considered as the portion of the kite that is on the lee side, so to speak, with respect to the wind. In Figure 2, thus, the front of the kite is the convex surface of the main part 60, shown as the surface faced to the left in Figure 2, while the rear portion of the body is the concave surface or face thereof. Thus, it will be noted that the flange portions 19, 22 extend rearwardly from the front of the body, viewing the same as in Figure 2. In Figure 1, one is looking at the kite from the rear, while in Figure 4, one is observing the kite from the front. The outside surface of the shallowly-conical main part 60, that is, the convex surface thereof, defines the front of the kite.

Materials have not been specified herein, but obviously, they can be varied according to the desires of the manufacturer. The kite could be die formed from thin sheet aluminum, and in some forms, the strength of the skin may be sufficient to eliminate all or part of the framing. Then again, the frame can be made of a very light material such as balsa wood, while the skin may be a fabric. All of this, of course, is at the option of the particular manufacturer.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A kite comprising a shell-like body having at its front a main part disposed in a generally central position and having a shallowly conical shape, the convex surface of said main part defining said front of the body, said body having a lower flange portion projecting rearwardly from one segment of the periphery of said main part and having a generally frusto-conical shape, the body having an upper flange portion projecting rear-

wardly from the remaining segment of said periphery of the main part and arcuately bowed outwardly from the body.

2. A kite comprising a shell-like body having at its front a concavo-convex main part disposed in a generally central position of the body, the convex surface of said main part defining said front of the body, said body having a lower flange portion projecting rearwardly from one segment of the periphery of said main part and having a generally frusto-conical shape, the body having an upper flange portion projecting rearwardly from the remaining segment of said periphery of the main part and arcuately bowed outwardly from the body.

3. A kite comprising a shell-like body having at its front a main part disposed in a generally central position and having a shallowly conical shape, the convex surface of said main part defining said front of the body, said body having a lower flange portion projecting rearwardly from one segment of the periphery of the main part and having a generally frusto-conical shape, said lower flange portion being curved about the center of the main part, the body having an upper flange portion projecting rearwardly from the remaining segment of the periphery of the main part and arcuately bowed outwardly from the body.

4. A kite comprising a shell-like body having at its front a main part disposed in a generally central position and having a shallowly conical shape, the convex surface of said main part defining said front of the body, said body having a lower flange portion projecting rearwardly from one segment of the periphery of the main part and having a generally frusto-conical shape, said lower flange portion being curved about the center of the main part, the body having an upper flange portion projecting rearwardly from the remaining segment of the periphery of the main part and arcuately bowed outwardly from the body, said upper flange portion also being curved about the center of the main part.

5. A kite comprising a shell-like body having at its front a main part disposed in a generally central position and having a shallowly conical shape, the convex surface of said main part defining said front of the body, said body having a lower flange portion projecting rearwardly from one segment of the periphery of the main part and having a generally frusto-conical shape, said lower flange portion being curved about the center of the main part, the body having an upper portion projecting rearwardly from the remaining segment of the periphery of the main part and arcuately bowed outwardly from the body, said upper flange portion also being curved about the center of the main part, said lower and upper flange portions having lips at their back edges, the lips being curved about said center with the lip of the lower flange portion being curved on a radius slightly greater than that about which the lip of the upper flange portion is curved.

6. A kite comprising a shell-like body having at its front a main part disposed in a generally central position and having a shallowly conical shape, the convex

surface of said main part defining said front of the body, said body having a lower flange portion projecting rearwardly from one segment of the periphery of the main part and having a generally frusto-conical shape, said lower flange portion being curved about the center of the main part, the body having an upper flange portion projecting rearwardly from the remaining segment of the periphery of the main part and arcuately bowed outwardly from the body; and stabilizing means carried by said body.

7. A kite comprising a shell-like body having at its front a main part disposed in a generally central position and having a shallowly conical shape, the convex surface of said main part defining said front of the body, said body having a lower flange portion projecting rearwardly from one segment of the periphery of the main part and having a generally frusto-conical shape, said lower flange portion being curved about the center of the main part, the body having an upper flange portion projecting rearwardly from the remaining segment of the periphery of the main part and arcuately bowed outwardly from the body; and stabilizing means carried by said body, comprising a fin radiating from the center of the body and extending downwardly from said center to the periphery of the body.

8. A kite comprising a shell-like body having at its front a main part disposed in a generally central position and having a shallowly conical shape, the convex surface of said main part defining said front of the body, said body having a lower flange portion projecting rearwardly from the periphery of the main part and having a generally frusto-conical shape, said lower flange portion being curved about the center of the main part, the body having an upper flange portion projecting rearwardly from the periphery of the main part and arcuately bowed outwardly from the body, said lower flange portion extending over an angular distance of approximately 225 degrees of the circumference of the body, the upper flange portion extending over the remainder of said circumference.

9. A kite comprising a shell-like body composed of two segments integral with and merging smoothly into one another, said segments comprising an upper and lower segment, the segments having body parts together forming a shallow cone the convex surface of which defines the front of the body, the upper segment having a flange portion projecting rearwardly from the periphery of the body part of the upper segment and arcuately outwardly bowed from the body, the lower segment having a flange portion also projecting rearwardly from the body of the lower segment and formed to a frusto-conical shape.
